UNITED STATES PATENT OFFICE.

LORENZO D. ROBERTS, OF SHAWANO, WISCONSIN.

SLIDE MEMBER FOR CALCULATING MACHINES.

Application filed June 23, 1926. Serial No. 118,035.

This invention relates to improvements in calculating machines, the particular object being to improve the slide or slide members, by which certain arithmetical calculations are carried out.

Other objects and advantages appear in the following specification, reference being had to the accompanying drawing, in which—

10 Figure 1 is a plan view illustrating a general arrangement of the calculating machine in which the improved sliding member is employed.

15 Figure 2 is a longitudinal section taken substantially on the line 2—2 of Figure 1, showing the improved slide or sliding member in place.

Figure 3 is a detail perspective view of the slide alone,

20 Figure 4 is a detail perspective view of the enlarged end or head of the tablet employed in connection with the slide.

Reference may be had to my patent for calculating machines 917,134 of April 6, 25 1909, and for a calculator 990,779 of April 25, 1911, the former disclosing the slide or sliding member to which the improvement is directed, with some particularity.

Briefly describing the calculating machine, 30 10 represents a base or frame consisting of a rectangular shallow box, preferably 1" or less in depth, open at the front or face thereof and having a hinged end 11 at the right carrying a stay bar 12 which is provided 35 with guide pins 13 fitting in corresponding openings in the end 11 and which is adjusted in its position by means of set screws 14 threaded in the end 11 and bearing thereon.

The adjustability of the stay bar is to 40 enable it to bear against the ends of a series of narrow strips forming guides 15, which bear at their other ends against the left end of the frame and which alternate with a series of shorter strips forming slides 16, the 45 stay bar thus preventing the longitudinal movement of the guides 15 while the slides 16 are free to be moved between the guides from one end to the other of the frame. To afford a ready means for moving the slides 50 each is provided with a loop or knob 21 at its right hand end.

It is with the slides that the invention is concerned and the description is therefore confined to one of them, they all being alike. 55 The slide 16 is composed of a bar usually of wood having enlargements 17 and 18

along one of the longitudinal edges (Fig. 3), the former serving to strengthen the slide around a recess formed in the opposite edge. The recess is composed of a slot 19 which 60 terminates in a rounded transverse opening 20.

That portion of the slide at the left of the foregoing recess may be known as the tablet end inasmuch as it is upon this end that 65 the tablet 22 rests when applied. Inasmuch as the tablets are subject to substitution and change to meet the requirements of the calculating machine the arrangement is such that both can be made expeditiously.

At one end the tablet has an enlarged head 23 (Fig. 4). This is produced by bringing the end of the tablet around a short section of rounded wood or the like. The extremity of the tablet is suitably secured to 75 the adjacent main body so as to hold the rounded wood in place. In applying the tablet to the tablet end of the slide, the enlarged head 23 is slipped into the recess 70 19—20. The tablet is then stretched along 80 the tablet end, down over the extremity of the slide to a place underneath where it is first impaled upon a pin 24 and then held by a metallic or other clip 25. This clip is at present arranged to swing upon a stud 85 or pivot 26, but the clip may be arranged otherwise.

It is upon the tablet 22 that the rate per cent is marked. This is subject to variation, and the tablets are therefore capable of 90 being removed from the slide and replaced as already stated. At a suitable place along the upper edge of the slide a slight depression 27 receives a suitable marker 28 bearing a numeral which coacts with one of the 95 columns of the machine. The formerly described enlargements 17 and 18 are made by cutting away unnecessary portions of the bar on the underside or edge. It is in the cut-away portion at the extreme left (Fig. 100 3) that the pin 24 and clip 25 are housed. The enlargements 17 and 18 provide bearings which ride upon the floor of the box (Fig. 2).

It may also be noted that the portion 17 is 105 larger than the portion 18. The latter acts in the capacity of a fulcrum for it is readily seen that a downward pressure upon the slide in the vicinity of the knob or loop 21 will in turn produce downward pressure on 110 the remote extremity of the slide, keeping such extremity down and the enlargement or

bearing 17 in engagement with the bottom of the box. The value of the particular manner of mounting the tablet 22 serves to eliminate hooks, clamps, etc., on the upper side. The upper side is therefore left free and unobstructed. The clip 25 is practically full width of the slide; the slide is movable between the guide bars 15, these contacting the slide at each side. This circumstance insures that the clip 25 shall remain in holding position, it being impossible for the clip to accidentally move out of position over the end of the tablet 22 with the result of the possible release of the tablet.

15 It is in the latter respect, namely, concerning the clip 25 and guides 15, that there exists a combination between the slides 16 and the guides. The function of the latter, in addition to keeping the slides separated, is to confine the clip 25 so that its grip upon the extremity of the tablet 22 may not be lost. Such combination exists also in connection with the enlarged head 23 of the tablet, for it is by means of the adjacent guides 15 that said head is prevented from slipping out edgewise from the recess 19—20.

20 While the construction and arrangement of the improved calculating machine slide is that of a generally preferred form, obviously modifications and changes may be made without departing from the spirit of the invention or the scope of the claims.

I claim:—

1. A slide member for the purpose described comprising a bar having a recess formed transversely of one edge, a tablet consisting of a flexible strip being applicable to the bar and having an enlarged head insertible in the recess, enlargements formed on the opposite edge providing bearings for the slide and being produced by cutting away portions of the slide, and means situated in one of the cut-away portions by which the remaining end of the tablet is gripped and held.

2. A slide member for the purpose described comprising a bar having a transverse recess formed at one longitudinal edge, a tablet applicable to the bar having an en-

larged head insertible in the recess, and enlargements on the opposite edge of the bar providing bearings for the slide, one of said enlargements being situated opposite to the recess, thereby strengthening the bar at an otherwise weak point.

3. A slide for the purpose described comprising a bar having a transverse recess at one edge being composed of a slot and a rounded transverse opening, a tablet composed of a flexible strip having an enlarged head at one end insertible in said recess, said tablet being drawn over the adjacent end of the bar, enlargements formed on the opposite edge of the bar by cutting away portions of the bar, one of said enlargements being situated opposite the recess to strengthen the bar, means situated in one of the cut away portions in which the tablet drawn over said end is entailed, and means also situated in said cut-away portion for gripping the extremity of the tablet to hold it in the entailed position.

4. A slide for the purpose described comprising a bar having a recess at one edge, said recess being composed of a transverse slot and an enlarged opening, a tablet composed of a flexible strip applied to the bar having an enlarged head at one end occupying said opening, said tablet extending out at the slot, enlargements formed on the opposite edge of the bar by cutting away portions of the bar, means situated at one of the cut-away portions upon which the tablet is impaled after being brought around the adjacent end of the bar, and a movable clip also situated in said cut away portion for gripping the extremity of the tablet and holding it in place upon the impaling means.

5. In a calculating machine, the combination of a slide, an indicia-bearing tablet applied to the slide, a revoluble clip by which one end of the tablet is held, and guides at the sides of the slide defining a passageway for the slide and confining the clip to prevent disengagement thereof from said tablet.

LORENZO D. ROBERTS.
